UNITED STATES PATENT OFFICE

2,346,160

FUEL INJECTION APPARATUS

Louis O. French, Milwaukee, Wis.

Application April 4, 1941, Serial No. 386,763

12 Claims. (Cl. 123—139)

The invention relates to fuel injection apparatus and more particularly to liquid fuel injection mechanism for internal combustion engines.

The most widely used fuel injection pumps today provide a period of low pressure at the beginning of the delivery stroke, a high delivery pressure, and then a release of the high pressure through the operation of a by-pass valve usually formed by cooperative ports between the piston and its barrel whose operation is varied by rotating the piston relative to the barrel. In most of these pumps the timing of the beginning of injection as determined by the pump is constant and the timing varied by varying the angular advance of the pump drive cam. Manufacture of the pumps above described requires considerable precision machine work including the cutting of relief edges on the plungers and the careful fitting of the plunger rotating mechanism which included toothed parts for each cylinder. Owing to the large amount of machine work that has to be done and the care that has to be exercised in the manufacture of these pumps, the cost is high, and this to some extent has interfered with a more widespread sale of high speed Diesel type engines. Furthermore, only relatively skilled mechanics understand the operation of these pumps.

The object of the present invention is to provide a pump which accomplishes the general result of the more complicated and costly pumps above described but which may be produced much more cheaply than said prior pumps and includes a few simple parts whose actions are readily visible while the pump is operating and easily understood and which also has certain advantages hereinafter referred to over said by-pass valve type pumps. More particularly, the invention embodies a pump whose plunger is timed by the engine and driven on its delivery stroke through a drive connection which may be rendered ineffective to drive the plunger during and at different points of the available delivery stroke from full stroke to no stroke to vary the amount of fuel delivered to the engine and whose release permits a quick return of the plunger, independent of the control of the drive connection, to its initial position. With such a means for controlling the movement of the plunger the construction of the pump itself is greatly simplified, as the plunger may be a plain round rod reciprocating in a plain round bore and preferably adapted to over-run an inlet port in the barrel during the initial part of its delivery stroke, be released from the engine drive while in full motion on the delivery

stroke and return quickly independent of engine speed to its initial position, thus producing a quick drop in pressure and insuring a sharp cut off of the discharge valve which may be the injection valve of the engine or a valve controlling the operation of such injection valve. As a further advantage in the quick return of the plunger, the time for filling the pump from its plunger controlled suction port is increased, thus insuring a better charging action and an opportunity to increase the speed range of the engine.

The invention further consists in the several features hereinafter set forth and more particularly defined by claims at the conclusion hereof.

15 In the drawings:

Fig. 1 is a vertical sectional view through a fuel injection device embodying the invention;

Figs. 2 and 3 are views similar to Fig. 1 showing the parts in different operating positions, parts being broken away;

Fig. 4 is a detailed vertical sectional view taken on the line 4—4 of Fig. 1, parts being broken away;

Fig. 5 is a view similar to Fig. 1 showing certain modifications, parts being broken away.

Fig. 6 is a detailed sectional view showing certain modifications;

Fig. 7 is a detailed sectional view showing certain modifications.

30 The invention relates to fuel injection apparatus which may be used in multi-cylinder arrangements to furnish fuel to separate fuel injectors associated with the combustion chambers of an engine or passages leading thereto or which may be used as a so-called unit injector with the pump built into the injector casing.

Referring to Figs. 1 to 4 of the drawings, the numeral 10 designates a casing of bronze or other suitable metal having axially aligned bores 11 and 12 and a cross bore 13 in which end caps or plugs 14 and 15 are mounted. An engine controlled and operated plunger actuator member 16 is slidably mounted in the bore 11 and is keyed thereto by a pin 17 working in slots 18 in said casing normally covered by an oil sealing sleeve 19 removably mounted on said casing. A spring 20 urges the member 16 into engagement with one end of a medially pivoted lever 21 whose other end is urged by said spring against an engine driven cam 22 which may be designed to impart either constant velocity or uniformly accelerated motion or any desired kind of controlled motion to the pump plunger on its delivery stroke.

45 A plunger follower 23 is slidably mounted in

the bore 12 and bears against a pump plunger 24 which reciprocates in a barrel 25 provided with diametrically disposed inlet ports 26, a spring 27 normally moving the parts 23 and 24 to bring the plunger 24 above said ports.

A breakable or releasable drive connection between member 16 and follower 23 is provided by a drive connector member 28, forming a finger, pivotally mounted on the pin 17 between the forked ends of the member 16 and formed at its other end 29 to ride over a surface provided on a flat sided projection 30 formed on the follower 23 with which surface it is in thrust connection until released by an adjustable cam or trip control member 31 pivotally supported on the plug 14 and providing a control surface 32 with which a part 33 of the member 28 is normally held in contact by a spring 34. The surface 32 is in a chordal plane either at or close to the center of rotation of the control member 31 which provides a maximum arc of adjusting movement for said member and makes it easy to operate. The projection 30 is guided against turning during reciprocation of the plunger between the flat surface of the plug 14 and inner edge of the plug 15. The plugs 14 and 15 may be secured in position by hook bolts 35 whose heads engage over the plug 14 and whose shanks pass through holes in the casing and in the outer flange of the plug 15. The plug 14 is angularly adjustable so as to adjust the control member 31 relative to the finger 28. The member 31 has an arm 31' secured thereto which may be either manually or governor operated.

During the inward or delivery stroke of the member 16, the finger 28 thereon pushes on the follower 23 and thus moves the plunger 24 inwardly to first overrun and cut off the ports 26 and then force the fuel past the spring closed discharge valve 36 and through piping to a separate hydraulically operated fuel injector valve (not shown but of conventional form) or through nozzle passages 37 of a unit injector into the engine cylinder or its supply manifold. During this delivery stroke depending upon the adjustment of the control 31, the member 28 is pushed outwardly or laterally along (see Fig. 2) and finally from the top of the projection 30 (see Fig. 3) until its driving connection therewith is broken, and as soon as this occurs, the motion of the plunger 24 is immediately reversed and the spring 27 acts to return it to its initial position as shown in Fig. 3 regardless of the position at that time of the member 16 and finger 28 which it will be noted is so formed as to permit this return movement without its interference. Thus with this arrangement injection may always start at the same time or be changed through any suitable advance or retard mechanism associated with the cam 22 or its shaft and continue for full stroke or for any desired fractional amount of full stroke to no stroke, without changing the rate of injection as determined by the cam 22, by the angular shifting or rotating of the control member 31 which does not produce any side thrust on the plunger and which operates so easily that it is advisable to provide a certain amount of frictional effort to turn it. The quick return stroke of the plunger even at starting, insures the efficient operation of the pump at low engine speeds.

Shifting the control 31 so that the finger's stroke relative to the projection 30 is reduced causes the release of the finger therefrom sooner in the stroke of member 16 with the result that the plunger 24 is given a shorter stroke until

finally the finger 28 is prevented from contacting the projection 30 at all, and no fuel is delivered.

In the modification shown in Fig. 5 the engine controlled member 40 is slidably keyed to a hardened steel bushing 41 by a pin 42 working in slots 43 in said bushing, said pin having the finger 44 pivotally mounted thereon. This finger at its lower end bears against a surface 45 on the outer end of a lever 46 which is pivotally mounted on an eccentric 47 whose shaft 48 is journalled in a casing 49 of aluminum alloy or other light weight metal. The outer end of the lever 46 has a rounded part 50 which bears against the top of a pump plunger follower 51 that is slidably mounted in a hardened steel bushing 52 secured to the casing 49. A fixed trip surface 53 is secured for limited range of initial adjustment to the casing 49 by screws 53'. A spring 44' normally holds the finger 44 in contact with the surface 53. The general operation of this form is the same as that previously described, but in this form the amount that the finger 44 is displaced by the trip surface 53 remains constant while the effect of this displacement on the stroke of the plunger is varied by moving the lever 46 lengthwise relative to the finger through the adjustment of the eccentric 47. Upward movement of the lever 46 is limited by a stop pin 46'.

Instead of a unit injector or a separate pump, the invention may be embodied in a form shown in Fig. 6 which has certain advantages of both these types. In this form instead of the plunger follower having a part directly engaged by a tappet operated member there is a hydraulic operating column between these two parts which takes the place of the usual lever and push rod of a lowered cam shaft arrangement, or the lever of a more elevated cam shaft, so that the cam shaft may be in the lowered position of the valve cam shaft in the usual L-head and overhead valve engines.

The pump, a unit with the injector, is formed by a plunger 54 working in a barrel 55 mounted in a casing 56. The barrel has inlet ports 57 supplied with fuel through grooves 58 that may be connected with a supply line 59 also shown connected by a conduit 62 with a space 60 formed by the casing 56 and a cylinder 61 in threaded engagement therewith. A spring closed outwardly opening discharge valve 63 controls the flow of fuel to the spray passages 64. The plunger is normally moved outwardly on its suction stroke by a spring 65, and its upper end has a non-centering contact with a hydraulically operated piston 66 reciprocating in the cylinder 61 which is connected by piping 67 to a similar cylinder 68 in which a piston 69 having a suitably guided projection 69' reciprocates, this piston being similar to the plunger follower 23 of the first described form and similarly operated by a pivoted finger 70 mounted on a reciprocatory tappet member 71 held by a spring 72 in engagement with the timing and operating engine driven cam 73 mounted on a shaft journalled in a housing 74 that may form part of the crank case of the engine or be formed as a separate unit therefrom if desired. The tappet member 71 is slidably keyed by finger pivot pin 75 to a sleeve 76 secured to the housing 74. The finger is controlled by a control member 77 similar to member 31 against which it is yieldingly held by a spring 78. The operation of this arrangement is similar to the first described form, the plunger

operating force being transmitted through the hydraulic column between the pistons 66 and 69 whose diameters are considerably greater than the diameter of the plunger 54, so that the hydraulic operating pressure may be low compared to the fuel injection pressure. To keep the hydraulic system supplied with fluid the plunger 66 may have an opening 79 in it normally closed by a check valve 80 and its spring 81 but permitting passage of fluid from the space 60 to the piping between the pistons 66 and 69 at periods of low pressure. The piping 67 may include a riser 82 closed by a plug 83 to assist in the initial priming of the system. The hydraulic fluid may as here shown be a part of the fuel delivered to the space 60 by a fuel pump working against a spring closed relief valve (not shown) of from five to ten pounds pressure, or the supply of fuel to the injector may be separate and a heavier oil such as a lubricant may be delivered to the space 60 and used in the hydraulic system.

Some forms of spray nozzles or fuel injectors require that fuel be furnished to them at relatively high velocity, so that on starting or at low engine speeds they do not work efficiently. Where the apparatus embodying the present invention is to be used with such equipment instead of the engine controlled member being operated directly by an engine driven cam it may be operated by a spring motor whose action is timed by the engine but which causes the finger carrying member to be operated at substantially the same rate regardless of engine speed, and in Fig. 7 I have shown one such motor for this purpose in which an oscillatory shaft 84 is moved in one direction by a lever 85 secured thereto and held by a spring 86 against a suitable engine operated cam (not shown), said shaft having a toothed disk 87 mounted thereon adapted for engagement with a pawl 88 yieldingly held against said disk by a spring 89. The pawl 88 is pivotally connected by a pin 90 with a reciprocator member 91 which is guided in a cylinder 92 and keyed by the finger pivot pin 93 working in slots 94. An energizing spring 95 is interposed between a shoulder 96 on the member 91 and a flange 97 on the cylinder. The clutch finger 98 is mounted on the pivot pin 93 and is similar to the finger 28 or 70 and adapted to cooperate with the plunger follower members previously described and the control member 31 or 71. With this structure movement of the disk 87 in an anti-clockwise direction pulls upwardly on the pawl link 88 and member 91 against the pressure of the spring 95, thus storing up energy in said spring 95 and moving the finger 98 back from a release position shown with finger 28 in Fig. 2 to the initial position shown in Fig. 1 and in this position the continued movement of the disk 87 causes it to push the pawl 88 out of engagement with it and permit the spring 95 on its releasing its compression to push the member 91 and consequently the finger 98 outwardly independently of engine speed and thus operate the pump plungers of the structures previously shown and described. It is to be noted that the finger 98 may be in a release position for a considerable period of engine crank travel without effecting the follower which it operates and which is free to allow the return of the pump plunger independent of engine speed, and the amount of energy to operate the plunger may be the same at all speeds and regardless of the load.

I desire it to be understood that this invention is not to be limited to any particular form or ar-

rangement of parts except as such limitations are included in the claims.

What I claim as my invention is:

1. In a fuel injection apparatus for internal combustion engines, the combination with a reciprocator pump plunger and a spring for moving said plunger on its non-delivery stroke, of engine controlled means for moving said plunger on its delivery stroke including a trippable member, and control trip means operable during the delivery stroke to trip said trippable member to render said engine controlled means ineffective to move said plunger to thereby control the effective stroke of said plunger and permit said spring to quickly return said plunger immediately after tripping is effected and independently of the speed of said engine controlled means.
2. In a fuel injection apparatus, the combination with a reciprocator pump plunger and a spring for moving said plunger on its non-delivery stroke, of an engine-controlled plunger actuator, means including a breakable drive connection connecting said actuator with said plunger including relatively movable thrust transmitting members, and control means operable during the delivery stroke of said actuator to move said members relative to each other for causing the breaking of said drive connection during the delivery stroke of the plunger to determine the effective stroke of said plunger and to permit said spring to quickly return said plunger immediately after the breaking of said drive connection and before and independently of the return of said actuator.
3. In a fuel injection apparatus for internal combustion engines, the combination with a reciprocator pump plunger and a spring for moving said plunger on its non-delivery stroke, of a reciprocator engine controlled member provided with a pivoted clutch finger, a reciprocator plunger operating member operatively connected to said finger, and a trip means for releasing said finger for varying the stroke of said plunger operating member as compared to said engine controlled member.
4. In a fuel injection apparatus, the combination with a reciprocator pump plunger and a spring for moving said plunger on its non-delivery stroke, of an engine controlled reciprocator member provided with a pivoted clutch finger, a plunger moving member provided with a projection in thrust engagement with said finger, and a rotatably adjustable finger deflector member with which said finger engages during the delivery stroke to release said finger from thrusting engagement with said projection and permit the quick return of said plunger independent of said engine controlled member.
5. In a fuel injection apparatus, the combination of a casing having aligned bores and a bore at right angles thereto, an engine controlled reciprocator member slidably mounted in one of said aligned bores and provided with a movable clutch finger, a pump plunger operating member slidably mounted in the other aligned bore and provided with a projection for thrust engagement with said finger, plugs for the ends of said right angle bore and forming guides for said projection, and a finger deflector member rotatably mounted on one of said plugs for moving said finger out of thrust engagement with said projection during the delivery stroke of said plunger operating member.
6. In a fuel injection apparatus, the combination of a casing, an engine controlled reciprocator member slidably mounted in said casing and provided with a releasable clutch finger, a

finger deflector member mounted in said casing, a pump plunger operating member slidably mounted in said casing, a lever between said finger and plunger operating member and in thrust connection therewith, said lever being shiftable to vary the effective thrust connection between said finger and lever under the action of said deflector member during the delivery stroke of said reciprocating member.

7. In a fuel injection apparatus, the combination of a casing having aligned bores and a bore at right angles thereto, an engine controlled reciprocating member slidably mounted in one of said aligned bores and provided with a pivoted clutch finger, a pump plunger operating member slidably mounted in the other aligned bore and provided with a projection for thrust engagement with said finger, plugs for the ends of said right angle bore and forming guides for said projection, one of said plugs being angularly adjustable relative to said casing, means for securing said last named plug in adjustable position, and a finger deflector member rotatably mounted in said angularly adjustable plug for moving said finger out of thrust engagement with said projection during the delivery stroke of said plunger operating member.

8. In a fuel injection apparatus for internal combustion engines, the combination with a reciprocating pump plunger and a spring for moving said plunger on its non-delivery stroke, of an engine-controlled plunger actuator, a drive connection between said actuator and said plunger including relatively movable members, and control means operable during the delivery stroke of said actuator to move said members relative to each other to render said drive connection ineffective to move said plunger to thereby control the effective stroke of said plunger and permit said spring to quickly return said plunger immediately after said drive connection is rendered ineffective and before and independently of the return of said actuator.

9. In a fuel injection apparatus for internal combustion engines, the combination with a reciprocating pump plunger and a spring for moving said plunger on its non-delivery stroke, of an engine-controlled plunger actuator, means including a releasable drive connection having relatively movable thrust transmitting members connecting said actuator with said plunger, and control means for causing the release of said drive connection during the delivery stroke of the plunger to vary the stroke of said plunger as compared to said actuator and free said plunger from the control of said actuator to permit said spring to return said plunger immediately after the release of said drive connection and during the de-

livery stroke of said actuator and at a rate of speed independent of the speed of the engine.

10. In a fuel injection apparatus for internal combustion engines, the combination with a reciprocating pump plunger and a spring for moving said plunger on its non-delivery stroke, of a reciprocating engine controlled member provided with a movable drive connector, a reciprocating plunger operating member, said drive connector having a driving connection with said plunger operating member, and means for varying the stroke of said plunger operating member as compared to said engine controlled member including means for releasing said connector from its driving relation in said connection to free said plunger from the control of said engine controlled member and permit said spring to return said plunger immediately after the release of said connector and before and independently of said engine controlled member.

11. In a fuel injection apparatus for internal combustion engines, the combination with an injector including a reciprocating pump plunger, of plunger operating mechanism including a constant stroke engine timed member and variable stroke thrust member for imparting variable strokes to said plunger from the same initial position and without changing the beginning of the injection period and permitting of the release of said plunger from the control of said engine timed member, means including a spring for quickly returning said plunger directly at the end of any stroke less than full stroke and independently of the speed of the engine and immediately after the release of said plunger from said engine timed member, and means distinct from said plunger-return-spring for returning said engine timed member.

12. In a fuel injection system for internal combustion engines, the combination with a reciprocating pump plunger and a spring for moving said plunger on its non-delivery stroke, of a plunger actuator, means controlled by the engine for operating said actuator at a rate independent of the speed of the engine, a drive connection between said actuator and said plunger including relatively movable members, and control means operable during the delivery stroke of said actuator to move said members relative to each other to render said drive connection ineffective to move said plunger to thereby control the effective stroke of said plunger and permit said spring to quickly return said plunger immediately after said drive connection is rendered ineffective and before and independently of the return of said actuator.

LOUIS O. FRENCH.
